DESIGN FOR A COFFEE MAKER

Herbert G. Lehmann, Wood-Ridge, N. J., assignor to Casco Products Corporation, Bridgeport,
Conn., a corporation of Connecticut

Application April 13, 1940, Serial No. 91,660

Term of patent 14 years

To all whom it may concern:

Be it known that I, Herbert G. Lehmann, a citizen of the United States, residing at Wood-Ridge, in the county of Bergen and State of New Jersey, have invented a new, original, and ornamental Design for a Coffee Maker, of which the following is a specification, reference being had to the accompanying drawing, forming part thereof.

I claim:

The ornamental design for a coffee maker, as shown.

HERBERT G. LEHMANN.
